CLAIM

(21) Appl. No.: **29/157,360**

I claim the ornamental design for a combined air freshener and elastic band for mounting on a ceiling fan blade, as shown and described.

(22) Filed: **Mar. 19, 2002**

DESCRIPTION

(51) LOC (7) Cl. **23-04**

FIG. 1 is a perspective view of a combined air freshener and elastic band for mounting on a ceiling fan blade embodying the design of the present invention, on a reduced scale, the air freshener is shown with the top open;

(52) U.S. Cl. **D23/366**

FIG. 2 is a front elevational view thereof;

(58) Field of Search D23/366-9; 422/120,

422/122-4; 239/211, 34-60

FIG. 3 is a rear elevational view thereof;

422/122-4; 239/211, 34-60

FIG. 4 is a left side elevational view thereof, the right side elevational view being a mirror image thereof;

422/122-4; 239/211, 34-60

FIG. 5 is a top plan view thereof;

422/122-4; 239/211, 34-60

FIG. 6 is a bottom plan view thereof; and,

422/122-4; 239/211, 34-60

FIG. 7 is a perspective view thereof, on a greatly reduced scale, the broken line drawing of a ceiling fan blade is for illustrative purposes only and forms no part of the claimed design.
